UNITED STATES PATENT OFFICE

2,217,778

PHASE MODULATION

George L. Usselman, Port Jefferson, N. Y., assignor
to Radio Corporation of America, a corporation
of Delaware

Original application October 26, 1935, Serial No.
46,857, now Patent No. 2,159,237, dated May 23,
1939. Divided and this application December
15, 1937, Serial No. 179,841

7 Claims. (Cl. 179—171.5)

For various reasons it has been found desirable
in the radio and allied arts to signal by means
of alternating current of substantially constant
amplitude, the current being modulated in one
5 or more of its other characteristics at signal fre-
quency. I propose to supply such a need by pro-
viding a novel and simple means whereby wave
energy of substantially constant amplitude may
be modulated in phase at signal frequency.

10 This application is a division of my United
States application #46,857 filed October 26, 1935,
U. S. Patent #2,159,237, dated May 23, 1939.

More in particular, this application concerns
15 a phase modulator or oscillator, or high frequency
vacuum tube relay stage, wherein phase modu-
lation of the high frequency energy is obtained
by virtue of the phase shift in the feedback
energy occurring with over or undue neutraliza-
tion or, in other words, by regeneration or degen-
eration. This effect may be accompanied by a
small amount of amplitude modulation and a
much larger amount of phase modulation if the
change in neutralization is not carried too far,
and especially if the driving energy or excitation
25 energy is strong.

In a modification, I provide means for pro-
tecting the tubes of the modulator or oscillator
stage or relay stage in the event of defective
operation of any of the circuits thereof.

30 In describing the essential features of my in-
vention, reference will be made to the drawing
in which the single figure illustrates a circuit
diagram in accordance with a preferred embodi-
ment of the invention.

35 The single figure of the drawing shows, for
purposes of illustration only, circuit arrange-
ments comprising the essential features of a
phase modulation system wherein phase modula-
tion is accomplished by over-neutralizing or
40 under-neutralizing the thermionic stage through
which the wave energy is passed. In the circuit
of the single figure wave energy to be modulated
is fed to the input of an electron discharge tube
having a plate circuit including a neutralizing
45 portion and including two impedances control-
lable in opposition at signal frequency to thereby
control the state of neutralization or lack there-
of to control the phase of the output energy.

Referring to the drawing, and in particular to
50 the single figure of the drawing, V_1 is an electron
discharge tube of the thermionic type having its
control grid 2 coupled by a grid circuit 5, 6, R
to an inductance coupled with a source of carrier
wave energy 8. The tube V_1 has its anode con-
55 nected by an inductance 4 and choking induct-
ance RFC and blocking condenser 9 to its cath-
ode. The inductance 4 is coupled to the induct-
ance 10 in an output circuit which may lead to
any utilized device directly or by way of ampli-
60 fiers and frequency multipliers and amplitude

limiters, etc. The circuit 3, 4, may be tuned to
the frequency of the source 8 in the event the
oscillations are to be repeated or amplified only,
or to a harmonic of said frequency in the event
the stage V_1 is also to act as a frequency multi-
plier. A point on the inductance 4 may be cou-
pled to the control grid 2 by means of a neu-
tralizing condenser NC. The circuit described
herein comprises a high frequency relay or am-
plifier or frequency multiplier. The means for
10 phase modulating the high frequency energy in
the relay will now be described.

Modulating potentials from source 7 are im-
pessed by way of a transformer T in phase op-
position on the control grids 12, 12' of modulator
15 tubes V_2 and V_3 . Impedance elements Z_1 and
 Z_2 are connected across the inductance 4 by
means of the variable capacities 3, 3'. The
anodes 11 and 11' of tubes V_2 , V_3 are connected
as shown to the impedances Z_1 and Z_2 . The
20 cathodes of tubes V_2 and V_3 are connected to
the other terminals of the impedances Z_1 , Z_2 and
to the cathode of V_1 and to ground. The im-
pedances Z_1 , Z_2 may be inductive or may be a
combination of inductance and resistance. Po-
25 tential for the anode of tube V_1 is supplied from
a direct current source connected to the induct-
ance 4 by way of the radio frequency choke RFC.
Biassing potential for the grids of tubes V_2 , V_3
20 is supplied from a source 12, connected as shown
between a point on the secondary of T and the
cathodes of tubes V_2 , V_3 . Heating current for
the cathode of tube V_1 is supplied from any source
14 connected therewith, as shown.

In describing the operation of the phase modu-
lator of the single figure of the drawing, it will
be assumed that the stage V_1 is normally neu-
tralized by the circuits including the condenser
NC. In this case, the reactance of the condenser
35 NC equals the plate-to-grid reactance of tube
 V_1 . Also assume that the stage V_1 is receiving
high frequency wave energy from 8 and deliver-
ing the high frequency energy amplified or fre-
quency multiplied or amplified and frequency
40 multiplied to the output circuit 10. Also assume
that the audio frequency energy from source 7
is being supplied to the transformer T, and in
addition, take an instant when the grid 12 of
modulator tube V_2 is positive, and the grid 12'
45 of modulator tube V_3 is negative. This condition
causes the combined impedance of Z_1 and V_2
50 to decrease and that of Z_2 and V_3 to increase.
Now, the tank circuit 3, 4 is unbalanced so that
it is no longer neutralized with respect to the grid
circuit 5, 6, R. In this case, regeneration takes
55 place or there is a tendency to regeneration be-
cause energy is fed back through the neutralizing
condenser NC (now being at a higher radio fre-
quency voltage) to the grid 2 of V_1 , thereby
overbalancing the energy fed back by way of the
60

internal capacity of the tube from the anode to the grid. In this case, the phase of the energy or oscillations in the anode circuit 3, 4 is advanced ahead of the phase of the oscillations in 5 the grid tank circuit 5, 6.

Now, if we assume an instant in the radio frequency cycle when the grid of V_3 is positive and the grid of V_2 is negative, conditions will be reversed. The combined impedance of V_3 and Z_2 10 will be reduced and the combined impedance of V_2 and Z_1 will be increased. This causes an unbalance in neutralizing again because the high frequency voltage of the anode and of the circuit 3, 4 is now higher than the high frequency voltage 15 of the neutralizing end of the tank circuit 3, 4. In this case, more energy is fed to the grid 2 of tube V_1 from the anode thereof than by way of NC, thereby causing degeneration or a tendency of degeneration, and the phase of the high frequency oscillations in the circuit 3, 4 is 20 retarded with respect to the high frequency oscillations in the grid circuit 5, 6.

It will be seen that with reversal of the direction of current from the audio frequency source 25 7, corresponding changes in phase will take place in the high frequency energy in the output of stage V_1 . The frequency of phase shift corresponds to the audio frequency and the degree or amount of phase shift or modulation corresponds 30 to the intensity or amplitude of audio frequency energy. The direction of phase shift corresponds to the direction of audio current.

Phase modulated energy output from stage V_1 35 may be used in any manner desirable. It may be amplified, multiplied in frequency, limited as to amplitude, or one or more of said operations may be accomplished and the energy may then be transmitted over wires or over an antenna.

I claim:

40 1. In a phase modulation system a thermionic tube having an anode, a cathode, and a control grid, alternating current circuits connected between the control grid and cathode of said tube and between the anode and cathode of said tube, 45 means for impressing wave energy to be modulated on said grid and cathode, means for neutralizing the capacity between the anode and control grid of said tube, and means connected with said tube for upsetting and restoring said 50 state of neutralization at signal frequency to produce degeneration and regeneration in said tube and circuits to thereby vary at signal frequency the phase of the wave energy in the alternating current circuit connected with the anode and 55 cathode of said tube relative to the phase of the impressed wave energy.

2. In a phase modulation system, a thermionic tube having an anode, a cathode and a control grid, an alternating current circuit connected between the control grid and cathode of said tube, 60 an output circuit connected to the anode and cathode of said tube, means for causing wave energy to be modulated to flow in said circuits, a voltage transfer path, including a reactance of 65 the order of the reactance in the path between the anode and control grid of said tube, connected between a point on said output circuit and the grid end of said alternating current circuit whereby said tube and circuits are neutralized as 70 to the wave energy flowing in said circuits, and means operated at signal frequency for controlling the voltage transferred over said respective paths.

3. In a phase modulator, a thermionic tube 75 having an anode, a cathode and a control grid,

a circuit for applying wave energy to said control grid and cathode, an alternating current circuit coupled to said anode and cathode, a neutralizing circuit coupled between said alternating current circuit and said control grid to neutralize the capacity between the anode and control grid of said tube, a variable impedance connected with said neutralizing circuit, and a source of modulating potentials connected with said variable impedance.

4. In a phase modulator, a thermionic tube having a control grid, a cathode and an anode, an alternating current circuit connected to the control grid and cathode, an alternating current circuit including an inductance connected with the anode and cathode, a neutralizing condenser connecting a point on said inductance to the control grid of said tube, variable reactances connected in series in shunt to said inductance, a source of modulating potentials connected in phase opposition to said variable reactances, and means for applying a driving potential to the control grid of said tube.

5. In a phase modulator, a thermionic tube having a control grid, a cathode and an anode, 25 an alternating current circuit connected to the control grid and cathode, an alternating current circuit including an inductance connected with the anode and cathode, a neutralizing condenser connecting a point on said inductance to the control grid of said tube, variable impedances connected in series in shunt to said inductance, a connection between a point on said impedances and the cathode of said tube, means for applying modulating potentials in phase opposition to said variable impedances, and means for applying a driving potential to the control grid of said tube.

6. In a phase modulator in combination, amplifying means including an electron discharge 40 tube system having electrodes including a grid and anode connected in input and output circuits respectively wherein high frequency currents are caused to flow, a reactance in said output circuit connected to said anode, a pair of dissimilar voltage feedback paths from said output to said input circuit, one of said paths comprising the capacity between said anode and control grid and the other path comprising a capacity coupling said reactance to said input circuit, and means 45 for varying the ratio of energies fed back through said feedback paths in accordance with signalling potentials to thereby vary the phase of the high frequency currents caused to flow in said output circuit comprising a pair of modulating tubes 50 having their impedances shunting said reactance and modulated differentially by signal potentials.

7. In a phase modulator in combination, an electron discharge tube system having electrodes connected in input and output circuits wherein 60 high frequency currents are caused to flow, a reactance in said output circuit, a pair of dissimilar feedback paths from said output to said input circuit one of said paths comprising a capacity between tube electrodes the other comprising a 65 capacity connecting said reactance to said input circuit, an impedance of the tube type connected in shunt to said reactance and differentially modulated in accordance with signalling potentials to thereby differentially control the voltage fed back over said respective paths and consequently vary the phase of the currents flowing in said output circuit.
